(57) **CLAIM**

The ornamental design for an expandable shelf, as shown and described.

DESCRIPTION

FIG. 1 is a perspective view of the expandable shelf in a retracted configuration;

FIG. 2 is a perspective view of the expandable shelf in an expanded configuration;

FIG. 3 is a front elevational view of the expandable shelf in the retracted configuration;

FIG. 4 is a rear elevational view of the expandable shelf in the retracted configuration;

FIG. 5 is a left side elevational view of the expandable shelf in both the retracted and the expanded configurations, the opposite side of which is an identical mirror image;

FIG. 6 is a top plan view of the expandable shelf in the retracted configuration; and,

FIG. 7 is a bottom plan view of the expandable shelf in the retracted configuration.

The features shown in broken lines form no part of the claimed design.
